INDEX DEVICE

Walter T. Gollwitzer, Cleveland, Ohio, assignor,
by mesne assignments, to Addressograph-Mul-
tigraph Corporation, Cleveland, Ohio, a cor-
poration of Delaware

Application September 15, 1934, Serial No. 744,117

22 Claims. (Cl. 129—16.8)

This invention relates to means for indexing plates, cards, separators, etc., whereby they may be readily divided into two groups. This enables a set of address printing plates, for instance, to be classified into a group which will be utilized in printing and a group which will be omitted as the set passes through the printing machine. More particularly, my index device is of the class known as a "switch-tab" comprising a projecting member pivotally mounted on the address plate and adapted to be swung into either of two positions so as to indicate either visually or to a mechanical selector the "take-it-or-leave-it" character of the plate at that time.

My invention is concerned with the combination of the switch tab and the specially formed plate carrying the same, as well as with the tab individually and the plate individually. Objects of the invention are to provide such switch tab, and the plate portion carrying the same, so devised that the tab may be readily applied to the plate; and when applied, will remain firmly affixed to the plate but at the same time may be readily shifted as desired from one position to the other and will hold itself in either set position against inadvertent displacement, and will not be liable to distortion in use.

Another object is to so arrange the parts that the plates equipped with such switch tabs will not be liable to interfere with each other, either when stored in a drawer or stacked in a printing machine. Another object is to so form the tab that, in either position, it may effectively cooperate with a corresponding portion of the selecting mechanism of an addressing machine.

To the above ends, I have provided by this invention a tab having a central tongue at its lower end, which is arranged for automatic pivotal engagement with a suitable keeper on the plate upon insertion of the tab. I have further provided on the tab an intermediately located spring tongue provided with a shoulder which is adapted to coact with either of two retaining shoulders on a strap carried by the plate along which such portion of the tab may move. I have provided the tab with a projection above the plate strap which forms a guide preventing any other plate being hung onto the strap, and I have formed the upper end of the tab in a manner enabling it to present an effective transverse abutment for the selecting mechanism. All of these characteristics will be more fully hereinafter explained in connection with the drawing, which shows an approved form of my tab and plate.

In the drawing, Fig. 1 is a front elevation of an address plate to which the tab is applied, the index card of the plate being broken away to disclose the construction of the plate behind it; Fig. 2 is a perspective of the tab itself; Figs. 3, 4 and 5 are fragmentary views of a portion of the plate, illustrating respectively the front face with the tab applied, the front face without the tab, and the rear face with the tab applied; Fig. 6 is a longitudinal section through a portion of the plate and tab, as indicated by the line 6—6 on Fig. 1; Fig. 7 is a section through the tab and plate along the central axis of the tab, as indicated by the line 7—7 on Fig. 1; Fig. 8 is a view similar to Fig. 7, illustrating the tab in the act of being shoved into plate.

The plate may be a mere separator, or it may be a printing plate and have characters embossed or otherwise formed on it. I have shown it, however, as a carrying plate or frame 10 on which is mounted a metal embossed printing plate A and an index card B. Suitable means are formed on the plate 10 for retaining the printing plate and card in place. These need not be here described, except to state that the upper edge of the plate is curled over at 11 at the top, which feature performs the double function of retaining the upper edge of the card and of stiffening the plate. Extending along the top portion of the plate, behind the index card, may be a series of keepers 12 to receive ordinary index tabs, whereby the plates may be classified according to the position of such tabs.

Coming now to my invention, my tab, designated 20, is shown on what is ordinarily a much enlarged scale in Fig. 2. It has at its lower end a tongue 21, which has a semi-circular under-edge as shown at 22. Concentric with this edge and located substantially at the junction of the tongue with the body of the tab is a small projecting semi-circular offset or shoulder 23. This offset is extending toward the front face of the tab. Above the tongue and offset I make in the body of the tab a downwardly formed approximately U-shaped cut 24, which leaves a spring tongue 25, preferably of trapezoidal form, anchored at its lower end to the body of the tab and normally projecting toward its rear face. On the front face of this tongue I make an indentation 26, which results in a projection 27 on the rear face.

The plate which is to carry the switch tab described is formed with a pocket 15 to receive the tongue 22 and a strap 17, which extends across the body of the tab. The pocket is made by

- making a longitudinal slit in the plate, which is formed of two straight lines 13 parallel to the upper edge of the plate and an intermediate downwardly facing semi-circular cut 14 connecting the straight lines. The metal of the plate below these cuts is forced rearwardly to provide the pocket, which is open at the front and has a semi-circular bottom 15a. Then the strap 17 above mentioned is made by making two slits 10 parallel with the top edge of the plate and forcing the intermediate portion rearwardly, as shown. This strap has two holes 18 and 19 in it, either of which is adapted to be occupied by the projection 27 of the tab.
- 15 With the plate constructed as described, the tab is shoved manually downwardly into place, passing beneath the strap 17 and the lower end entering the pocket 15. In this movement the offset 23, as shown in Fig. 8, engages the portion 20 16 of the plate, which remains between the pocket 15 and the strap 17 and the two parts 16 and 23 are temporarily distorted sufficiently to allow the projection to pass beyond the portion 16. When the offset 23 passes the portion 25 16 the plate portion 16 and the offset 23 spring back into place and the tab becomes effectively, and practically permanently, anchored to the plate, as illustrated in Fig. 7.
- When the tab has been mounted, as described, 30 the projection 27 stands in front of the strap 17. The resilience of the tongue 25 allows its projection 27 to readily pass across the plate strap 17, the strap camming the tongue back into the general plane of the tab in this movement, as illustrated in Fig. 8. When the tab is 35 in its anchored position, shown in Fig. 7, the projection 27 has come into the range of the holes 18 or 19 and occupies one or the other of them according to whether the tab is in one extreme 40 position or the other, as illustrated in full lines and dotted lines respectively in Fig. 1.
- The offset shoulder 23 forms a permanent but 45 pivotal anchorage for the tab so that it is retained on the plate but may readily swing thereon. The lower end of the tab being concentric about the center of the semi-circular offset, the action is identical whether the shoulder 23 is in absolute contact with the semi-circular portion 14 of the plate or the tongue is in contact with 50 the bottom 15a of the pocket. The resilient tongue 25 normally retains the projection 27 in one or the other of the openings 18 or 19, but allows it to be cammed out of such opening by a sufficient pressure against the edge of the 55 tab. Accordingly, the tab, while permanently locked to the plate, may be readily shifted from one position to the other, but when given either position is not liable to accidental displacement therefrom.
- 60 The strap 17, which forms the guide and retainer for the tab 20, projects rearwardly from the plate slightly more than the keepers 12 of the ordinary tabs, to enable sufficient looseness to provide for ready swinging of the tab 20. To 65 prevent this rearward projection from forming an abutment on which the curled-over edge 11 of a plate directly behind the strap could catch, I provide a projection 28 on the tab (formed by an indentation 29 on the face of the tab directly 70 above the tongue 25) which stands idly a short distance above the upper edge of the strap 17. This projection provides in effect a cam directing anything beyond the strap 17. Accordingly, as 75 the curled-over edge 11 of one plate would lie directly behind the projection 28 it is kept from

encroaching on the space above the strap 17 and hence cannot become entangled therewith.

In certain types of addressing machines, selecting pins or shoulders are provided which 5 coact with the extreme end of the switch tab. For instance, in Fig. 1, I have illustrated at C a pin which when it engages the tab will insure the printing of that plate, and at D, a pin which when it engages the tab will cause the skipping of the plate. In order that one or the 10 other of these pins may effectively engage the tab in the corresponding angular position thereof, I form the upper end of the tab with an angular recess 30, the obtuse angle of which is the supplement of the acute angle of swing of the tab. 15 By this provision the tab presents one shoulder 31 parallel with the top of the plate when the tab is in one position and another shoulder 32 which becomes parallel with it when the tab is in the other position. Thus, the tab may effectively coact with the controlling pins C and D of the selector and there is no tendency of the pressure of pins to cam the tab out of position.

My tab may be very effectively made out of a single piece of spring metal. The plate likewise 25 is preferably made of metal and the portions which cooperate with the tab are formed by cutting and pressure in a manner well understood. The tab may be readily inserted manually, but when in place remains permanently anchored 30 to the plate. The spring tongue provides sufficient force to prevent inadvertent displacement of the tab while allowing it to be manually swung on its pivot, as desired.

I claim:

1. The combination of a plate to be indexed and a tab adapted for pivotal attachment thereto, said tab having its lower end formed into a central tongue with a rounded projection on the face of the tab adjacent the junction of the tongue 40 and body, said projection being abrupt on its upper edge, and the plate having a pocket adapted to be occupied by the lower portion of the tongue; the material of the plate above the pocket having a recess to receive the projection.
2. The combination of a plate to be indexed and a tab adapted for pivotal attachment thereto, said tab having its lower end formed into a tongue with a rounded lower edge and a projection with a rounded top and substantially concentric with said lower edge, the plate having an 50 upwardly facing pocket with a rounded bottom adapted to be occupied by the lower portion of the tongue, and the material of the plate above the pocket having a downwardly facing rounded recess adapted to be occupied by the projection.
3. The combination of a plate having an offset portion to provide a pocket open on one face and at the top, an offset strap formed on said plate out of the material thereof a short distance 60 above the pocket and on the same face of the plate, and a tab adapted to extend across the inner face of the strap and to have its lower end occupy the pocket, said tab having a projection adapted to engage the lower edge of the 65 material of the plate between the pocket and strap.

4. The combination of an index tab with a plate to be indexed, said plate having an offset strap with two shoulders thereon, the tab adapted to 70 be pivotally connected to the plate and having a spring tongue adapted to coact with either shoulder.

5. The combination of a plate having an offset portion to provide a pocket open on one face and 75

5 at the top, an offset strap formed on said plate out of the material thereof a short distance above the pocket and on the same face of the plate and provided with two shoulders, and a tab adapted to extend across the strap and to have its lower 10 end occupy the pocket, said tab having a projection adapted to engage the lower edge of the material of the plate between the pocket and strap and having a spring tongue adapted to 15

10 act with either shoulder of the strap.

6. The combination of a plate having an offset strap adjacent the upper edge and a keeper below the strap, a tab adapted to extend across the strap and have its lower end pivotally anchored in the keeper, said tab having a spring tongue carrying a projection and the strap having two holes adapted to be respectively occupied by the projection according to the position of the tab.

20 7. The combination of a plate having an offset strap adjacent the upper edge and an upwardly facing pocket below the strap and offset from the same side of the plate, and a tab adapted to extend across the strap and have its lower 25 end occupy the pocket and be pivotally anchored therein, said tab having a spring tongue carrying a projection and the strap having two holes adapted to be respectively occupied by the projection according to the position of the tab.

30 8. The combination of a plate having a strap near its upper edge and a tab extending transversely beneath said strap and limited in position thereby, said tab having a projection above the strap adapted to form a camming guard 35 with reference to the strap.

35 9. The combination of a plate having an upwardly opening pocket and a strap above the pocket, both the pocket and strap being offset from the plate on the same side thereof, and a tab extending transversely beneath the strap and having a tongue at its lower end occupying the pocket, and a projection formed on the tab directly above the strap to form a guard therefor.

40 45 10. A tab having a head at its upper end and formed adjacent its lower end into a central tongue with a projecting shoulder abrupt toward the head of the tab and located adjacent the junction of the body and tongue, whereby the tab may be pivoted.

50 55 11. A tab having means for pivotally attaching it near its lower end to a retaining device and having intermediately a spring tongue carrying a projection adapted to coact with recesses in the retaining device.

55 12. A plate to be indexed having a pocket depressed from the material of the plate and open toward one face of the plate and open toward the upper edge of the plate, the plate having a strap depressed from the material of the plate 60 on the same side as the pocket and between the pocket and the edge of the plate, the material of the plate between the strap-depression and the pocket having its lower edge recessed at the pocket, and the strap having a pair of openings 65 through it whereby a tab with a lower shoulder and an intermediate projection may be pivotally mounted in the pocket and have the projection engage either opening of the strap.

70 75 13. The combination of an index tab and a member to be indexed, the tab having at its lower end a centrally located tongue provided with a projection extending normally from the face of the tongue, the upper edge of the projection being abrupt while the lower portion

thereof merges with the face of the tongue, and the member to be indexed having a recess adapted to be occupied by the projection in a manner to prevent the ready removal of the tab while allowing it to swing on a pivot formed by the 5 projection and recess.

14. The combination of a plate to be indexed and a tab adapted for pivotal attachment thereto, said tab having adjacent its lower end a projection merging at its lower end with the plane 10 of the tab and at its upper end normally presenting an abrupt shoulder out of the plane of the tab, the plate having a recess adapted to be occupied by the projection, whereby the tab may be readily inserted and will thereupon become 15 pivotally attached to the plate.

15. The combination of a plate to be indexed, having an upwardly opening pocket with an arcuate bottom, a tab having a central tongue correspondingly rounded at its lower end, and adapted to occupy the pocket and coact with the bottom thereof to prevent inward movement of the tab, and means for preventing outward movement of the tab while allowing it to swing back and forth.

20 25 16. A plate to be indexed having a pocket formed by offsetting the material of the plate, said pocket being open at one face of the plate and toward the edge of the plate, the portion of the plate which defines the top of the pocket 30 being recessed in its lower edge.

17. The combination of a plate to be indexed and an index tab, comprising a single strip of metal extending across the edge of the plate and pivoted adjacent its inner end directly to the 35 plate and adapted to swing through an angle while still projecting across the edge of the plate, means carried by the plate adapted to engage the tab between its pivoted end and its free end for holding it in either of two extreme positions, 40 the outer end of the tab being recessed at a re-entrant angle by substantially straight edges.

18. The combination of a member to be indexed provided with a pocket and an index tab whose lower end occupies the pocket, said tab 45 comprising a single strip formed adjacent its lower end with a centrally located projection connected with one face of the tab above the lower end thereof and inclining away from the tab toward the upper end thereof, so that the projection merges at its lower edge with the plane of the tab and at its upper edge presents an abrupt shoulder and coacts with the member to be indexed above its pocket to form a pivot.

50 55 19. A tab formed at its lower end into a central tongue with a rounded lower edge and a projection formed on the face of the tongue and being out of the plane thereof at the upper edge of the projection, said projection merging at its lower end with the plane of the tongue and having an abrupt rounded upper edge.

60 65 20. A tab made of a single piece of material and having at its lower end a central tongue materially narrower than the body of the tab and a shoulder projecting from the face of the tab adjacent the junction of the body and tongue, the upper edge of the shoulder being rounded and the lower end of the tongue being rounded, whereby the tongue is adapted to occupy a pocket in the member to be indexed while the projection may pivotally coact with a recess in 70 the member above the pocket.

75 80 21. A tab made of a single piece of material and having at its lower end a central tongue materially narrower than the body of the tab and a shoulder projecting from the face of the 75

tab adjacent the junction of the body and tongue, the upper end of the tab being recessed by an obtuse re-entrant angle.

22. The combination of a plate to be indexed formed adjacent its edge with a longitudinal depression of trapezoidal form providing a strap separated from the plate at its upper and under edges and connected at its ends integrally with the plate by portions which stand at an

acute angle to each other, said plate being formed with an upwardly opening pocket which is located directly below the strap in the narrow region between the lines defining the ends of the depression so that a tab having an end tongue occupying the pocket may swing either way against a firm abutment provided by the connections of the strap to the plate. 5

WALTER T. GOLLWITZER.
